UNITED STATES PATENT OFFICE.

BENJAMIN F. BAIN, OF PITTSBURGH, PENNSYLVANIA.

AUTOMATIC TOY.

1,244,455.

Specification of Letters Patent. Patented Oct. 30, 1917.

Application filed January 24, 1917. Serial No. 144,289.

To all whom it may concern:

Be it known that I, BENJAMIN F. BAIN, a resident of Pittsburgh, in the county of Allegheny and State of Pennsylvania, have invented a new and useful Improvement in Automatic Toys, of which the following is a specification:

This invention relates to automatic toys, and particularly to gravity-operated devices 10 of that class.

The object is to provide an improved toy, which will work continuously by weight of a charge placed therein, and a counterweight, until the charge has been carried 15 from the toy to a distance. For this purpose means are provided to discharge a small portion of the stored material at a time into a movable part of the device, which then operates by gravity to carry the load to another 20 point, there discharge it, and then is returned by a counterweight to the starting position to repeat the operation. All power is provided by means of gravity of a portion 25 of the charge being transported and of a counterweight. The purpose is to provide a toy which will continue to operate automatically for a considerable time by reason of a single charge so as to stimulate and hold the 30 interest of an average child, while at the same time furnishing an object lesson in mechanics and the operation of physical laws. Other objects are to provide a quick 35 acting device, having rapid movement of the transporting parts; simultaneous operation of the transporting and load measuring means; and the quick loading and unloading of the transporting means.

Referring to the accompanying drawings, Figure 1 is a side elevation of the toy, showing a car in load-receiving position; Fig. 2 is a partial section and plan of the track, the car and hoppers being removed; Fig. 3 is a side elevation of the toy showing a car in load discharging position; Fig. 4 is a front 45 elevation of the hopper and measuring receptacle; Fig. 5 is a front elevation of a load carrying car; Fig. 6 is a side elevation of a modified form of car and track; Fig. 7 is a view similar to that of Fig. 6, showing the 50 car in discharging position; and Fig. 8 is a front elevation of the modified car and track as shown in Fig. 6.

The device in the form here illustrated comprises an inclined plane 1 consisting of

a metal sheet pressed to form a raised central portion 2, with parallel depending portions at each side, forming tracks 3. This runway is supported by two uprights 4, having a rigid cross bar 5 adapted to engage the runway by a notch therein, in such manner as to be rigidly locked in position when the parts are in normal position, but detachable by turning the uprights at an acute angle to the track. A resilient metal base member 6 engages the hooked ends of the 65 uprights by eyes 7. By spreading the ends of base 6 outward, they are readily disengaged from the uprights 4. The member 6 has an upwardly bent portion 8 adapted to engage notches 9 in the track member near its lower end. By this arrangement the track and its supports are readily taken apart for boxing in a small container.

Upon the upper ends of uprights 4, a conical charge holding hopper 10 is fastened by 75 any suitable means, as by rivets 11. Fixed to this hopper by supporting members 12, is a measuring, or supplementary hopper, 13. Both hoppers are open at top and bottom; the outlet 10^a in the bottom of the main hopper being small, and the outlet at the bottom of the supplementary hopper being large, compared to each other and to their respective capacities. A gate valve 14 is pivoted 80 by a pin 15, and wings 16 to the measuring hopper 13, and is adapted to normally hang below the outlet 17 of hopper 13, and to close that opening. To the bottom of valve 14 is riveted a weight 18 and a rigid arm 19, adapted in the closed position of the valve to 85 depend vertically.

A car having a body 20, on fixed trucks 21, and wheels 22, is adapted to run on the track above described. The lower end of the car is closed by a lift gate 23, in the form of a plate with rigidly attached members 24, extending parallel with the car bottom and pivoted to the rear end of the car body by pins 25. By this means the gate 23 is attached so as to close the forward end of the car normally, but is free to be lifted to allow a load to be discharged thereunder. The upper edge of the car is turned outward to form projecting lips 26 which prevent the gate from being lifted clear of the car. A cross member 27 is riveted to the gate, and has depending ends 28, carrying supplementary wheels 29, which are adapted to engage

- and ride on supplementary tracks 30. These tracks consist of plates fastened to the main runway near its lower end by pins 31, the tracks being formed by an angle in said 5 plates, providing flat tracks outside the main tracks and in the line of travel of wheels 29. These supplementary tracks have upturned terminals 32, and notches 33 adapted to engage and seat on base member 8.
- 10 The car is attached by a cord 34, running over a pulley 35, carried at the upper end of the track member, to a counterweight 36, somewhat heavier than the empty car.
- The operation of the device is as follows:—
- 15 Normally the gate valve 14 is held in closed position by weight 18 and depending arm 19, as shown in Fig. 3. With the car in position at the lower end of the track, the 20 hopper 10 is charged with sand, or any other suitable material that will flow readily through the outlet 10^a. The sand flows into the measuring hopper 13 which is of the proper size to contain just a car load. As 25 soon as the measuring hopper is filled, the outlet from the main hopper is closed by the banking up of the material itself and no more flows.
- After the main hopper is filled or charged, 30 the car is released, and is pulled to the top of the track by the counter-weight 36 and pulley arrangement shown in Fig. 3. When it comes under the hopper, the car strikes the arm 19 and forces it upward to the position 35 shown in Fig. 1. This moves the gate 14 to open the entire bottom of the supplementary hopper 13. Consequently, the measured contents of the lower hopper are instantly discharged into the car, while very little 40 material flows from the hopper 10 through the relatively small outlet 10^a, until the car, by reason of the load discharged into it, has moved down the track. Then the gate 14 returns to position to close the measuring 45 hopper, and the refilling thereof continues during a large part of the travel downward and back of the car. By reason of the slow filling and quick discharge of the lower receptacle, discharge of material from the 50 main hopper is almost continuous, adding greatly to the interest of a child in its operation, and the car receives its load almost instantly upon arrival at the top of its travel. This latter feature makes the travel 55 back and forth of the car practically continuous, since it loads and discharges immediately upon arrival at the limits of its travel. And the quick loading upon arrival under the hopper renders it unnecessary to 60 provide mechanical means for retaining or locking the car in position for load receiving. This is an important advance over the prior toys of this class.
- The car moves downward by force of 65 gravity of its load to the bottom of the in-
- cline. There the wheels 29 ride on supplementary tracks 30 and lift the end gate 23 so that the contents of the car is discharged thereunder. As soon as this is done, the car is pulled up by the counterweight, and again receives a load from the hopper, as above described. The operation is continuous until the main hopper is emptied into the receptacle 37. Whereupon the sand may be returned to the hopper to start the operation all over again.
- While I have described an inclined plane and car thereon, it will be obvious that the features of a small opening in the main hopper, a load measuring supplementary hopper, a gate valve controlling the entire bottom of the lower receptacle adapted to be operated by travel of a load receiving member,—whereby I secure a prolonged flow of material from the main hopper, a quick discharge of a measured load immediately on arrival of the load transporting member, and the closing of the bottom of the measuring receptacle as soon as the load is discharged—may be applied to other forms of 85 toys besides a car on an inclined plane, and will be equally desirable in such other forms. Therefore I do not limit my invention to the specific toy here described, and there are other features of the toy illustrated and described and hereinafter claimed which are not dependent upon the presence of the load measuring supplementary hopper, such for instance, as the specific forms of the transporting means and the gates for discharging 90 the load therefrom, and I wish it understood that the claims hereinafter made which do not include the load measuring feature are not to be construed as dependent upon the specific form of load supply means illustrated and described herein.
- An important novel feature of the toy illustrated and described is a car having a non-tilting body, but provided with a discharge outlet and a valve for closing the 100 outlet. One form of such car and discharge outlet with closure for same is illustrated in Figs. 1 to 5. Figs. 6, 7 and 8 illustrate a modification of the car, having a discharge opening in its bottom instead of at its end, 105 and having a horizontally instead of a vertically swinging valve for closing the same. As shown in Figs. 6, 7, and 8, the modified car comprises a body 20^a, and wheels 22^a, fixed to the body by members 21^a. The car has a flared top 37, and is hopper shaped, the walls meeting in a bottom of comparatively small area, which is open, forming an outlet 38, controlled by the swinging gate valve 39. This valve has lateral wings 40 which are 115 attached to the car body by pins or rivets 41. At the rear of the gate is a wall 39^a preventing the forward travel thereof beyond normal closed position. The sloping rear end of the car allows the gate valve to swing 120
- 125 130

backward to free the outlet 38. An arm 42 is fixed to the bottom of the gate valve and normally depends vertically therebelow. When this car is used, the supplementary tracks 30 are unnecessary. Instead, the middle portion of the inclined plane member 1, is cut out to form a slot 43, through which the arm 42 depends.

When this car is loaded from measuring hopper 13, or any other means, at the top of the track, it moves downward as stated in reference to the first described car. At the bottom of the track the arm 42 strikes the end 44 of slot 43, and the gate valve is thrown back to the position shown in Fig. 7, whereupon the load immediately discharges into receptacle 37, and the car returns to the top of the track, the gate valve moving back to closed position as the car starts upward.

The device is simple, does not readily get out of order, and works regularly and easily.

I claim:—

- 25 1. An automatic toy, comprising an inclined track, a car thereon, a concial hopper situated over the track and having a small opening at its bottom, a supplementary hopper situated under the opening from the main hopper and having its entire bottom open, a valve controlling the bottom of the secondary hopper and adapted to be operated by movement of the car, and means to discharge material from the car at the lower end of the track, and to return the empty car to position under the supplementary hopper.
- 30 2. An automatic toy, comprising an inclined track, a car thereon adapted to be held normally in position at the upper end of the track by a counterweight, a hopper above the upper end of the track, a supplementary hopper beneath the main hopper, a valve operated by movement of the car controlling the outlet from the supplementary hopper, and means to discharge flowing material from the car at the lower end of the track without tilting the car.
- 35 3. An automatic toy, comprising an inclined track, a car thereon, means to deliver a measured load of flowing material to the car upon its arrival at the top of the track, and means at the bottom of the track to open the gate controlling an outlet from the car, whereby its load is discharged without tilting the car.
- 40 4. An automatic toy, comprising an inclined track, a car movable thereon, a pulley at the upper end of the track, a cord attached to the car and to a counterweight adapted to draw the car upward on the track, a main hopper having a relatively small outlet at its bottom, a supplementary measuring hopper beneath the outlet of the main hopper and having a relatively large
- 45 outlet over the car in its raised position, a gate controlling the outlet from the supplementary hopper, a projection from said gate across the path of the car whereby the gate is opened upon arrival of the car at the upper limit of its travel, and means to discharge the load of the car upon its arrival at the lower limit of its travel.
- 50 5. An automatic toy, comprising an inclined track, a car thereon, a counterweight and pulley arranged to draw the car up the track, means to deliver a measured load of flowing material to the car upon its arrival at the upper limit of its travel, and means at the bottom of the track to open a gate controlling an outlet from the car, whereby its load is discharged without tilting the car.
- 55 6. An automatic toy, comprising an inclined track, a car thereon, a pulley and counterweight arranged to draw the empty car up the track, a conical load storage hopper situated over the upper end of the track and having a small opening in the bottom thereof, a supplementary hopper situated under the opening from the main hopper, and having its entire bottom open, a valve controlling the bottom of the supplementary hopper and adapted to be opened upon arrival of the car thereunder, supplementary tracks at a lesser inclination than the main track situated at the lower end thereof, a gate closing the lower end of the car, and wheels attached to said gate and adapted to ride on the supplementary tracks, whereby to lift the gate to discharge the load upon arrival of the car at the lower limit of its travel.
- 60 7. An automatic toy, comprising a load storing receptacle having a relatively small outlet at the bottom thereof, a supplementary measuring receptacle beneath the outlet from the main container having a relatively large discharge opening therefrom, a valve controlling the discharge opening from the supplementary container, and a transporting member operated by a counterweight to open the valve, and adapted to receive a load, carry it to a distance and then discharge it.
- 65 8. An automatic toy, comprising a load storing hopper, an outlet from said hopper of comparatively small size, a load measuring receptacle beneath the outlet of the main hopper, an outlet from the measuring receptacle of comparatively large size, and a valve controlling said large outlet, a depending arm attached to the valve, a load receiving and transporting car, a counterweight normally holding the car in position under the measuring receptacle and against the arm of the valve, and means to discharge the load from the car at a distance from the hopper.
- 70 9. An automatic toy, comprising a load storing hopper, a supplementary measuring receptacle beneath an outlet from the hopper, a valve controlling the bottom of the re-

ceptacle, a depending arm fixed to the valve, a car adapted to receive a load flowing from the measuring receptacle, means to move the car to a distance, means to discharge the load from the car, and means to return the car to a position to strike the arm of the valve and so to discharge the contents of the measuring receptacle into the car.

In testimony whereof, I have hereunto set my hand.

BENJAMIN F. BAIN.
